UNITED STATES PATENT OFFICE.

JOHN EDMUND BELLIVEAU, OF HALIFAX, NOVA SCOTIA, CANADA.

HINGE.

Application filed November 4, 1921, Serial No. 512,902, and in Canada September 23, 1921.

My invention relates to hinges that may be used on doors, covers or other similar objects capable of swinging.

The object of my invention is to devise a hinge of great rigidity especially when applied to thin material where screws afford very little grip on account of their shortness.

A further object is to construct a hinge having double leaves united by an integral strap, one of the leaves carrying integral pintle sockets or socket.

In the drawings forming part of the following description, where similar reference symbols refer to similar parts throughout the several views:

Figure 1 shows one part of my double leaf hinge blank, and

Fig. 2 shows the counterpart.

Fig. 3 shows the leaf blanks folded ready to receive the pintle.

Fig. 4 shows a hinge as applied to a door or casement.

Fig. 5 shows the application of one leaf of my hinge to a single leaf counterpart.

Fig. 6 shows my hinge applied to a chest or box.

In the drawings the leaf blanks have been shown of rectangular form, for the purpose of illustration only, as various other forms may be adapted. The blank shown in Fig. 1, designated by A, is cut partly crosswise at 1 and lengthwise at 2, forming straps 3 from which pintle sockets are formed. The length of the longitudinal cut 2 varies according to the thickness of the material where the hinge is intended to be applied. The counterpart blank shown in Fig. 2 designated by B has a cross cut 4 and longitudinal cuts 5 corresponding in length to the cut 2, Fig. 1, leaving a strap 6 to form a pintle socket. In Fig. 3 the blanks are shown bent, the bends being made at the dotted lines 7-7, Figs. 1 and 2, forming a part hinge, each having leaves 8, 9, separated by straps

10 and 11 having sockets 6 and 3, 3, into which a pintle such as 12 may be inserted. In Fig. 4 my hinge is shown applied to a door, window or similar swinging part 13 having a casement of equal thickness. In such cases the leaves on both parts of the hinge are equally distant. It will be understood, of course, that should the casement and the swinging part be of unequal thickness, the hinge would be shaped to accommodate both these parts. In Fig. 5 the hinge is composed of one part 15 constructed according to my invention, the counterparts 16 having but a single leaf. This form may be used where the thickness of the material permits the use of long screws. In Fig. 6 the hinge is shown applied to a box where the edge of the cover is flush with the outer side of the box wall. As illustrated, the screw holes in the hinge leaves are shown staggered, but it will be understood that in cases where the leaves should be held by rivets, these holes would be made to coincide.

The above description of my hinge is deemed sufficiently detailed to enable a clear understanding of its construction and working. Many variations may, however, be made without departing from the spirit of my invention as covered by the following claim.

I claim:

In a hinge construction, a hinge blank having a back and two sides integral therewith, an opening positioned centrally of said back, a pintle socket projecting outwardly of said back and integral with one of the sides in combination with a second blank having a back and two sides, and pintle sockets integral with one of the sides extending outwardly of said back and on each side thereof.

In witness whereof I have hereunto set my hand.

J. E. BELLIVEAU.
